UNITED STATES PATENT OFFICE.

CHARLES S. SCOTT, OF CHICAGO, ILLINOIS.

VENDING-MACHINE.

1,397,549.

Specification of Letters Patent.

Patented Nov. 22, 1921.

Application filed April 25, 1921. Serial No. 464,068.

To all whom it may concern:

Be it known that I, CHARLES S. SCOTT, a citizen of the United States of America, and a resident of Chicago, county of Cook, and 5 State of Illinois, have invented certain new and useful Improvements in Vending-Machines, of which the following is a specification.

This invention relates to vending machines particularly adapted for vending articles of ball shape, such as ball chewing gum and candy, but not necessarily limited to such articles.

The main objects of this invention are to 15 provide a check-controlled vending machine having an improved form and arrangement of parts for discharging two or more articles of merchandise at each operation; and to provide means for doubling the capacity 20 of the delivery mechanism without changing its lineal dimensions.

An illustrative embodiment of this invention is shown in the accompanying drawings, wherein—

25 Figure 1 is a vertical section of the vending machine.

Fig. 2 is a vertical section of the delivery mechanism, taken on the line 2—2 of Fig. 1, and showing the selectors at the completion 30 of their forward movement.

Fig. 3 is a front elevation of the housing for the delivery mechanism.

Fig. 4 is a view similar to Fig. 2, but showing the selectors at the completion of 35 their return movement.

Fig. 5 is a horizontal section of the delivery mechanism, taken on the line 5—5 of Fig. 2.

Fig. 6 is a rear elevation of the delivery 40 mechanism, showing part of the chute.

Vending machines are now in common use in which a check-controlled reciprocating member is arranged between the container and delivery outlet for delivering articles of 45 merchandise to the outlet. The arrangement of the parts in these machines is such that, during the forward movement of the reciprocating member, an article is delivered, and upon the return movement another 50 article is received from the container as a reserve supply. With these forms of ma-

chines, only one article is delivered at each operation.

In the present invention, the delivery mechanism comprises a reciprocating member which is formed to deliver an article upon its forward movement, and another article upon its return movement, so that two articles are delivered at each operation of the machine.

In the form shown, the vending machine comprises a base 1, supporting a container 2, and having arranged therein the improved delivery mechanism 3.

The supporting base is in the form of a 65 housing having a top plate 4, provided with an annular groove 5, which forms a seat for the lower edges of the container. Formed in the top plate 4, is a centrally located opening 6 providing communication between 70 the container and the delivery mechanism. To facilitate the movement of the articles of merchandise from the container, the plate 4 is inclined inwardly toward the central opening. Secured to the front wall of the 75 base is a suitable check-controlled operating mechanism 7, having a handle 8, connected to operate an inwardly extending crank 9 which is arranged to engage and actuate the delivering mechanism. A spring 10 is connected to the crank and is arranged to normally hold the reciprocating part of the delivery mechanism in the position shown in Fig. 4.

The container 2 is preferably transparent, 85 and is secured to the supporting base in any suitable manner. Interposed between the lower edges of the container and the top plate 4 is an annular gasket 11. The articles of merchandise are loosely arranged in 90 the container, and in the drawings these articles are shown as balls 12 of chewing gum or candy.

The delivery mechanism comprises a stationary housing or receptacle 13 having secured thereto a delivery chute 14, and having arranged therein a reciprocating member or receiver 15. The housing 13 is of box-like construction having the upper edges of its walls bent to form flanges 16 which 100 are rigidly secured to the lower face of the top plate 4. The housing 13 communicates

with the container through the opening 6. Formed in the front wall of the receptacle 13 is an arcuate slot or guide 17 through which the crank 9 extends for engagement 5 with the receiver 15.

The chute 14 is rigidly secured to the housing 13 and registers at its upper end with a centrally located opening 18 formed in the bottom of the receptacle in vertical 10 alinement with the opening 6 of the top plate 4. The lower end of the chute extends through an opening 19 formed in the supporting base below the check-controlled mechanism. Integrally formed at the upper 15 end of the chute is a projecting part 20 which is bent to provide a member which serves as a cut-off 21 extending forwardly through a slot 22 formed in the rear wall of the receptacle 13. The cut-off is arranged 20 directly above the opening 18 and in spaced relation to the base of the receptacle so as to control the delivery of articles through the chute.

The receiver is in the form of a slide 23 having a pair of downwardly extending tubular selectors 24 arranged in spaced relation and having their upper ends flared to provide bell mouths 25 registering with openings 26 formed in the slide. Extending 30 upwardly from the slide is a pair of spaced fingers 27 which project through the opening 6 for agitating the balls in the container. The slide 23 is mounted to reciprocate on guides 28 formed on the receptacle 13. The 35 selectors are formed to hold a plurality of balls in vertical arrangement. Formed in the tubular selectors are transversely disposed recesses 29 which are arranged to receive the cut-off 21 so as to permit the receiver to reciprocate relatively of the cut-off. The spring 10 is arranged to normally urge 40 the receiver into position for retaining one of the selectors in vertical alinement with the openings 6 and 18. Arranged forwardly 45 of the selectors is a wall 31, which is rigidly secured to the slide 23, and provided with a centrally located slot 32 for receiving the crank 9. The movement of the crank 9 along the arcuate slot 17, shifts the receiver 50 15 against the action of the spring 10 to bring the second selector into registry with the openings 6 and 18.

In the normal position of the delivery mechanism as shown in Fig. 1, one of the 55 selectors is located directly below the opening 6 in position to receive balls from the container. In this position the lowermost ball in the first selector rests upon the cut-off 21. Upon shifting the receiver to the left 60 of Fig. 4, to the position shown in Fig. 2, by means of the handle 8, the second selector is moved into registry with the openings 6 and 18 so as to receive a supply of balls from the container. In this last mentioned 65 position of the receiver, as shown in Fig. 2,

the lowermost ball in the first selector will have dropped to the bottom of the selector so as to rest upon the bottom of the receptacle 13, and the lowermost ball in the second selector will be resting upon the cut-off 70 21. In the initial operation of the machine, the second selector shown at the right of Fig. 2, does not deliver a ball, but only receives a reserve supply from the container. On the return movement of the receiver, the 75 lowermost ball in the first selector will be delivered through the opening 18, and the lowermost ball in the other selector will drop into the bottom of the receptacle 13, as shown in Fig. 4, where it is in position to be 80 delivered upon the next forward movement of the receiver.

Although but one specific embodiment of this invention has been herein shown and described, it will be understood that numerous details of the construction shown may be altered or omitted without departing from the spirit of this invention as defined by the following claims.

I claim:

1. A vending machine comprising a container, a delivery outlet, a movable receiver intermediate said container and outlet for delivering articles of merchandise to said outlet, and a member controlling the passage 95 of articles through said outlet, said receiver being shiftable back and forth beyond opposite sides of said member for delivering an article on its forward movement and another article on its return movement. 100

2. A vending machine comprising a container, a delivery outlet, a reciprocable receiver having a pair of selectors intermediate said container and said outlet for delivering articles of merchandise to said outlet, 105 said receiver being normally held in position to retain one of said selectors in registry with said outlet, and a cut-off controlling the passage of articles through said outlet, said selectors being shiftable across said 110 cut-off and beyond respectively opposite sides thereof whereby said receiver is adapted to deliver an article on its forward movement and another article on its return movement. 115

3. A vending machine comprising a container, a delivery outlet, a stationary cut-off mounted adjacently above said outlet, and a reciprocable receiver having a pair of vertically disposed selectors intermediate said 120 container and outlet for delivering articles of merchandise to said outlet, one of said selectors being normally held in registry with said outlet, said selectors being shiftable beyond respectively opposite sides of 125 said cut-off whereby said receiver is adapted to deliver an article on its forward movement and another article on its return movement.

4. A vending machine comprising a con- 130

tainer, a housing mounted adjacent the lower end of said container and having its base formed with an opening, a reciprocable receiver mounted in said housing and having
5 a pair of vertically disposed tubular selectors formed to hold articles of merchandise in vertical arrangement for delivering said articles to said opening, a stationary cut-off

mounted adjacently above said opening in spaced relation to said base, said selectors 10 being shiftable beyond respectively opposite sides of said cut-off.

Signed at Chicago this 22nd day of April 1921.

CHARLES S. SCOTT.
